UNITED STATES PATENT OFFICE

157,591

DRESS

Eulalie E. Hildebrand, New York, N. Y.

Application March 22, 1949, Serial No. 1,517

Term of patent 3½ years

(CL. D3—26)

To all whom it may concern:

Be it known that I, Eulalie E. Hildebrand, a citizen of the United States, residing in city of New York, county of New York, and State of New York, have invented a new, original, and ornamental Design for a Dress, of which the following is a specification, reference being had to the accompanying drawing, forming a part thereof, wherein:

Fig. 1 is a perspective view of my design for a dress from the front.

Fig. 2 is a perspective view of my design for a dress from the rear.

The sleeves are like the right sleeve shown in Fig. 2.

I claim:

The ornamental design for a dress, substantially as shown and described.

EULALIE HILDEBRAND.
